UNITED STATES PATENT OFFICE.

WILLIAM E. WINE, OF TOLEDO, OHIO.

LOCKING DEVICE FOR HOPPER-CAR DOORS.

Application filed February 27, 1922. Serial No. 539,580.

To all whom it may concern:

Be it known that I, WILLIAM E. WINE, a citizen of the United States of America, residing at Toledo, in the county of Lucas and 5 State of Ohio, have invented certain new and useful Improvements in Locking Devices for Hopper-Car Doors, of which the following is a specification.

My invention relates to new and useful 10 improvements in freight car door locking devices and in the present embodiment I have shown the device used in connection with a hopper type of car.

One of the objects of the present invention 15 is to provide a locking device which may be quickly and readily attached to a hopper and door and which will be relatively easy to operate when it is desired to both open and shut the door.

20 Still another object of the present invention is to provide a device consisting primarily of a hook; which may be secured to the hopper door; a plate which cooperates with the hook, which plate is to be secured 25 to the side of the hopper, the plate having formed thereon a lug which is engaged by the hook when the door is in its closed position; and a handle which is secured to the hook and passes beneath the plate secured 30 to the side of the hopper. A handle attached to a hook is of great advantage as it will save the trouble of having an operator climb under the car to reach the locking device.

35 Still another object of the invention is to provide a locking device for car doors wherein a hook is used which is provided with a relatively long handle so that the hook may be easily engaged with or disengaged 40 from a lug which is formed on a plate secured to the side of the hopper.

45 Still another object of the invention is to provide a car door locking device consisting of but few parts and wherein after the door is once locked it will be held from accidental opening, it being necessary to first release a dog by striking the same with a hammer, or bar or other instrument.

50 With these and other objects in view the invention consists in certain new and novel arrangements and combination of parts as will be hereinafter more fully described and pointed out in the claims.

55 Referring now to the drawings showing a preferred embodiment of the invention— Fig. 1 is a side elevation from beneath

the car showing a fragmentary portion of a hopper, a hopper door, and the improved locking device secured to the hopper and hopper door, the dotted lines showing the locking device disengaged and the hopper door swung to its open position.

Fig. 2 is a fragmentary end elevation.

Fig. 3 is a sectional view taken on line 3—3 of Fig. 1, and

Fig. 4 is a diagrammatic cross sectional view of a car, partly in elevation, showing the hoppers and the relative location of the locking devices.

At the outset, it may be mentioned, that 70 the device as here shown, is attached to what is known as a Barnett hopper car.

Referring now to the drawings and to Fig. 1 in particular, there is shown a portion of the outer side sheet 1 of a hopper, the bottom chute 2 and the hopper door 3 which is hinged as at 4, to a wall of the hopper. Secured to a side 5 of the hopper door 3 is a plate 6 having the downwardly formed extension 7 to which is pivoted a hook 8. 80 At the point 9, the hook being in an inverted position to that of the ordinary normal position of a hook. This hook 8 has the jaw 10 which forms the ledge 11 which ledge engages a lug or rib on a plate secured to the hopper (shortly to be described) 85 when the door is in its locked position.

Formed on the bottom edge of the hook is the outstanding extension 12 which has the ribbed sides 13 to partly encase one end 90 of a handle 14 which is riveted as at 15 to the extension 12, the handle having the bent portion 16 at its outermost end.

Secured to the side of the hopper and at the lower corner is the triangular plate 17 95 which is provided with three integral bosses 18 through which are passed rivets 19 to secure the plate to the side of the hopper, the bosses spacing the plate 17 away from the side sheet 1 of the hopper so that the handle 14 may pass between the plate 17 and the side of the hopper, the handle 14 being riveted to the hook 8 and bent at its outer end after the same has been passed beneath the plate 17.

100 Formed on the under side of this plate 17 is the elongated lug or rib 20 which is adapted to be engaged by the ledge 11 of the hook 8 when the door is in its closed position. Mounted on one of the bosses 18 110 is the dog 21 which, when swung to its closed position, as shown in Fig. 1, engages

the rear edge of the hook 8, tightly holding the same in engagement with the lug or rib 20. This dog 21 is provided with the projection 22 which forms a striking surface 5 when desired to release the dog and open the door, which opening is accomplished by grasping the bent portion 16 of the handle 14 and throwing the hook out of engagement with the rib 20.

10 It will be noted that the handle 14 is carried throughout the movement of the door by the hook 8 and at the same time is always beneath the plate 17 so that it will always be held from accidental loss or disengagement.

15 By providing a locking device of this character having the relative long handle 14, the locking or latching of the door in its closed position is much more easily accomplished than when just a hook is used as, of course, a greater leverage is obtained, and the handle extends outwardly nearly to the side of the car and may be operated without crawling under the car.

20 25 In most instances of the application of this device, a similar arrangement will be used on the opposite side of the hopper door and hopper so that the door will be supported and locked at both of its free ends.

30 35 From the foregoing it will be seen that it is a relatively easy matter to lock or unlock the hopper door and when once held in its supported position the door cannot become accidentally opened as the dog firmly holds the hook in engagement with the rib formed on the plate 17.

40 It will be understood, also, that many slight changes might be made or relative transposition of the parts, without in any way departing from the spirit and scope of the invention.

Having thus described my invention, what I claim as new and desire to secure by Letters Patent is:

45 1. In combination with a hopper car having a drop door, a hook pivotally mounted on the door, a bracket mounted on the side of the car hopper and having means thereon to cooperate with said hook to hold the door 50 in a closed position, a handle extending from said hook and passing beneath said bracket and of such length that a portion of the handle remains beneath the bracket throughout the travelling of the door.

55 2. In combination with a hopper car having a drop door, a hook pivotally mounted near its one end on the door, a bracket mounted on the side of the car hopper, and

spaced slightly therefrom, a lug on said bracket to cooperate with the hook to hold the door in a closed position, a handle secured to the lower end of said hook and said handle passing between the side of the hopper and the bracket, and the said handle being bent at its outer end so as to prevent its removal from beneath said bracket.

3. In combination with a hopper car having a drop door, a hook pivotally mounted on the door, a bracket mounted on the side of the car hopper and spaced from the said side, and said bracket provided with a lug to cooperate with said hook to hold the door in closed position and locking means for holding the hook in engagement with the lug on said bracket, a handle secured to the lower end of said hook and passing beneath said bracket, the handle being of such length that it remains beneath the bracket during the travel of said door and the outer end of said handle being bent to prevent any accidental disengagement of the handle from the bracket.

4. In combination with a hopper car having a drop door, a hook pivotally mounted on the said door, said hook having an extension formed on its lower end and a handle secured to said extension, a bracket secured to the side of the car hopper and spaced slightly therefrom, said handle extending beneath said bracket and of such length that it remains beneath said bracket throughout the travel of the door, the end of said handle being bent at an angle to the remainder thereof, said bracket being provided with a rib to be engaged by said hook when the door is in its closed position and means for locking the hook in engagement with said rib.

5. In combination with a hopper car having a drop door, a hook pivotally mounted on said door, said hook having an extension formed on its lower end and a handle secured to said extension, and said handle extending from the side of the car inwardly, a bracket secured to the side of the car hopper and spaced slightly therefrom, said handle extending beneath said bracket and of such length that it remains beneath said bracket throughout the travel of the door, the end of said handle being bent at an angle to the remainder thereof, said bracket being provided with a rib to be engaged by said hook when the door is in its closed position and means for locking the hook in engagement with said rib.

In testimony whereof I affix my signature. 115
WILLIAM E. WINE.
